UNITED STATES PATENT OFFICE.

THEOPHIL KOSCHADE, OF NORTH ADELAIDE, SOUTH AUSTRALIA, AUSTRALIA.

BURGLAR-ALARM.

1,219,957.

Specification of Letters Patent. Patented Mar. 20, 1917.

Application filed February 12, 1914. Serial No. 818,339.

To all whom it may concern:

Be it known that I, THEOPHIL KOSCHADE, a subject of the King of Great Britain, residing at North Adelaide, in the State of 5 South Australia, Australia, have invented certain new and useful Improvements in Burglar-Alarms, of which the following is a specification.

In devices of this character, heretofore known, reliance has been placed solely upon operation of the device upon tampering or opening movement of the door or window and such devices have not heretofore included means for initially locking a door or 15 window so that entrance could not be effected except by positively unlocking the door or window before moving the same into an opening position, and therefore it is the object of my invention to overcome this de- 20 vice in prior devices by necessitating the positive operation of the locking means to first unfasten the door or window before entrance can be attempted, such unfastening or unlocking movement serving, in ac- 25 cordance with my invention, to actuate the alarm.

Other features of novelty will be more fully described in connection with the accompanying drawing and will be more par- 30 ticularly pointed out and ascertained in and by the appended claims.

In the drawing:

Figure 1 is a face view showing the application of the device of my invention 35 mounted to secure a window.

Fig. 2 is a horizontal longitudinal sectional view through the structure disclosed in Fig. 1.

Fig. 3 is a detail view of a form of insu- 40 lation used in the device of my invention.

As illustrated, 1 designates a portion of a window sash and 2 designates a portion of a window frame. Mounting blocks 3 and, 45 4 are shown secured to the frame and sash, respectively, on which the device of my invention may be mounted.

I have shown a positive locking means in the form of a bolt lock wherein a keeper 5 is secured to the sash 3 by means such as 50 screws 6 and wherein the bolt sheath 7 is secured to the frame, or rather the mounting 4, by means such as screws 8. In the present construction I secure the keeper 5 to the block 3, and the latter may be secured 55 to the sash 1 by means such as screws 9. A

bolt 10 is provided with an operating shank 11 provided with a knob 12 thereon. The sheath 7 is provided with an unlocking slot 13 running longitudinally thereof, and locking slots 14 extending transversely of the 60 slot 13. It will be readily seen from the foregoing description, that when the bolt 10 is shot into the keeper and the shank 11 is in the position shown in Fig. 1, it will be impossible to raise or lower the window 65 without first retracting the bolt 10. The keeper 5 is to be located on the window in any desired location or I may have more than one keeper on the window sash.

I preferably insulate the keeper 5 and the 70 sheath 7, by mounting the same on blocks of fiber 15 and 16, respectively, as will be seen more clearly by reference to Fig. 2.

A circuit-closing member preferably in the form of a keeper 17, is also mounted 75 upon the insulating base 16 and is tubular in form so that when the bolt 10 is retracted it will be projected into the circuit-closing member 17. The member 17 may be mounted by means such as screws 18. I also desire 80 to insulate the member 17 from the sheath 7, and I provide a ring of insulating material, as indicated at 19, in Fig. 3, and which is provided with extensions 20 projecting between the flanges of the sheath 7 and the circuit-closing member 17.

I have shown the sheath 7 and the circuit-closing member 17 bridged in a circuit including conductors 21 and 22. Conductor 21 is connected as at 23 with the flange of 90 sheath 7, and the conductor 22 is connected as at 24, with the flange of circuit-closing member 17. A source of current 25 and a switch 26 are also included in the circuit. An alarm device, preferably of the audible 95 type in the form of a bell 27, is also included in the circuit.

It will now be clear that when the bolt 10 is retracted from the locking position shown to an unlocking position, or toward an un- 100 locking position, circuit will be almost instantly closed between the circuit-closing member 17 and the bolt 10, back through the sheath 7 to conductor 21. Thus an alarm will be given to arouse the household. Of 105 course a window would be locked in position at such a restricted elevation, or to provide such a restricted opening, as to prevent a burglar or other persons from surreptitiously entering through the window, 110

thereby necessitating unlocking of the window before it could be sufficiently raised to permit of entrance.

In cases where glass doors are used and 5 where it has been found that bolts have been unlocked by cutting the glass, the device of my invention is very advantageous.

It is believed that the operation and utility 10 of the device of my invention will be clearly understood from the foregoing description, and while I have herein shown and described one specific form thereof, I do not wish to be limited thereto except for such 15 limitations as the claims may import.

15 I claim:—

1. A burglar alarm device for doors or windows to be used in connection with an electric circuit comprising a positive locking means including a keeper on the sash and a 20 bolt sheath on the frame, a bolt in said sheath adapted to be shot into said keeper, a tubular circuit-closing member connected with one conductor of the circuit and disposed in alinement with said sheath to receive 25 the bolt when the same is moved toward an unlocking position, and means for connecting another conductor of the circuit with said sheath for closing circuit through

said bolt when the same is moved toward an unlocking position.

30

2. A burglar alarm device for doors or windows to be used in connection with an electric circuit comprising a bolt sheath to be connected with one of the members to be held and connected in one of the wires of the circuit, a bolt keeper mounted on the second member to be fastened in alinement with said bolt sheath, a bolt mounted in said sheath to be capable of movement into and out of said keeper, and an element mounted 35 in alined proximity to said sheath and insulated therefrom and connected with the remaining wire of the circuit, the parts being arranged in a relation that as the bolt is moved into the locked relation with the keeper contact with said element is precluded and as the bolt is moved to the released position the element is engaged and the circuit is completed.

40 In testimony whereof I affix my signature 45 in presence of two witnesses.

THEOPHIL KOSCHADE.
